FISHING ROD HOLDER OR THE LIKE

William A. Hiering, West Point Island, N.J., assignor to Ortley Company Ltd., West Point Island, N.J., a limited partnership of New Jersey

Application March 27, 1957, Serial No. 45,456

Term of patent 7 years

(Cl. D31—4)

Fig. 1 is a front elevational view of a fishing rod holder or the like embodying my new design;

Fig. 2 is a bottom plan view thereof; and

Fig. 3 is a left side elevational view thereof.

The rear of the fishing rod holder or the like is substantially plain.

I claim:

The ornamental design for a fishing rod holder or the like, as shown and described.
